UNITED STATES PATENT OFFICE.

HERMANN GUSTAV CARL FRAHM, OF HAMBURG, GERMANY.

MARINE VESSEL.

Application filed January 24, 1922. Serial No. 531,514.

To all whom it may concern:

Be it known that I HERMANN GUSTAV CARL FRAHM, a citizen of Germany, and a resident of Hamburg, Germany, have invented certain new and useful Improvements in Marine Vessels, of which the following is a specification.

This invention relates to marine vessels and has for its object to provide improved means for damping the rolling motion, whereby also the stability of the vessel is increased, even when the vessel is not laden, without decreasing the hold capacity of the vessel.

According to the present invention the side plating of the vessel is curved outwardly between the deck height and the bilge to accommodate anti-rolling chambers in the space formed between the side plating and the chord of curvature or a vertical plane passing through the upper strakes of the side plating. The centre of curvature is situated substantially on the normal water line of the vessel. The outer wall of the anti-rolling chamber at each side of the vessel is preferably constituted by the side plating, which is suitably perforated to provide for ingress and egress of water, the water chamber being enclosed on its inner side by suitable longitudinal bulkheads located on or outside the chord of curvature or vertical plane of the upper strakes of the side plating.

By this construction the anti-rolling chambers are located outside the normal hold space and the breadth of the vessel increased, thereby increasing its stability. The breadth of the vessel is also increased below the minimum draught water line of the vessel so that the stability of the vessel is increased even when the vessel is not laden. The arrangement also enables the provision of additional hold space below the anti-rolling chambers.

On the drawing annexed, a half midship-section of a marine vessel is illustrated showing the application of the present invention.

The normal hold space of the vessel is laterally determined by the plane A—B. According to the present invention the side plating of the vessel is curved outwardly at *a* between the upper strakes *b* and the bilge *c* to accommodate an anti-rolling chamber *d* in the space formed between the plane A—B

and the curved side *a*. The side plating *a* forms the outer wall of the chamber *d* and is perforated at *e* for the ingress and egress of water. The chamber *d* is enclosed on its inner side by longitudinal bulkheads *f*, *g* and *h*, the bulkhead *f* being preferably just outside the plane A—B as shown.

It will be readily seen from the drawing that the curve or protuberance *a* is an integral part of the ship's sideplating and that it is disposed about the mean draught water line *C* and below the minimum draught water line *D* so that, when the vessel is empty and floating at the water line *D*, the stability of the vessel will still be increased. It will also be seen that, instead of encroaching on the normal hold space, additional hold space is provided beneath the bulkhead *g*.

The upper portions of the water chambers *d* may be cross-connected by a pipe *k* controlled by a valve *l*.

Claims—

1. A marine vessel having its main plating curved outwardly between the deck height and bilge, the centre of curvature being substantially on the normal water line of the vessel, a longitudinal bulkhead fitted internally to said main plating so as to enclose a space between the curved plating and bulkhead and apertures in said curved plating for the free ingress and egress of water to and from said space.

2. A marine vessel having its main plating curved outwardly between the deck height and bilge, the centre of curvature being substantially on the normal water line of the vessel, and an anti-rolling water chamber formed on its outside by the curved plating and on its inside by inner longitudinal bulkheads located on or near the chord of curvature, said curved plating being perforated for the free ingress and egress of water to and from said chamber.

3. A marine vessel as specified in claim 2 in which the bulkheads enclosing the water chamber include a lower outwardly directed longitudinal bulkhead, providing hold space outside the chord of curvature and beneath the water chamber.

In testimony whereof I hereunto affix my signature.

HERM. FRAHM. [L. s.]
